MECHANICAL PENCIL

Hugo S. Hasselquist, Oak Park, Ill., assignor to
 Joseph Dixon Crucible Company, Jersey City,
 N. J., a corporation of New Jersey

Application November 9, 1944, Serial No. 562,592

28 Claims. (Cl. 120—18)

1

This invention relates to mechanical pencils and particularly to the "propel type" of pencil.

The invention has for its salient object to provide a mechanical pencil of the type specified that is simple and practical in construction and has a minimum number of parts.

Another object of the invention is to provide a pencil of the character specified so constructed and arranged that a maximum length of lead can be used either in one length or a number of shorter lengths.

Another object of the invention is to provide a pencil of the character specified so constructed that a new lead can be easily and quickly inserted.

Another object of the invention is to provide a pencil of the character specified so constructed that the lead can be inserted at the outer or cap end of the pencil.

Another object of the invention is to provide a mechanical pencil so constructed that it can be loaded from the cap end without removing or disturbing any parts.

Another object of the invention is to provide a mechanical pencil so constructed and arranged that if a length of lead longer than the pencil capacity is inserted the excess length will be automatically broken off as the lead feed member is actuated.

Further objects of the invention will appear from the following specification taken in connection with the drawings which form a part of this application, and in which

Fig. 1 is a longitudinal sectional elevation of a pencil constructed in accordance with the invention, the lead propelling member being shown in its retracted position;

Fig. 2 is a fragmentary sectional elevation similar to Fig. 1 but showing the lead propelling member disposed at the outer end of its operative feeding movement or at the end of its operative path of travel;

Fig. 3 is an enlarged, transverse sectional elevation taken substantially on line 3—3 of Fig. 1;

Fig. 4 is an enlarged, transverse sectional elevation taken substantially on line 4—4 of Fig. 2;

Fig. 5 is an enlarged elevation of the plug member at the outer end of the barrel;

Fig. 6 is a top plan view of the lead feeding member;

Fig. 7 is an end elevation of the member shown in Fig. 6;

Fig. 8 is an enlarged, fragmentary sectional elevation showing the connection between the inner end of the tip and the barrel;

2

Fig. 9 is an end elevation of the inner end of the barrel;

Fig. 10 is a longitudinal sectional elevation of the cap end of the pencil illustrating another embodiment of the invention;

Fig. 11 is a longitudinal sectional elevation similar to Fig. 1 but illustrating another embodiment of the invention;

Fig. 12 is a view similar to Fig. 11 but illustrates the lead feeding member in its retracted position;

Fig. 13 is a transverse sectional elevation taken substantially on line 13—13 of Fig. 11;

Fig. 14 is an elevation of the plug at the rear end of the barrel, this view being taken at right angles to Figs. 11 and 12;

Fig. 15 is a side elevation of the lead feeding member; and

Fig. 16 is a bottom plan view of the lead feeding member shown in Figs. 11 and 12.

In the particular embodiment of the invention illustrated in Figs. 1 to 10 inclusive, the pencil comprises a barrel 10 which may be formed of any suitable material, such as wood or plastic. A tip 14 is secured to the barrel at one end thereof, the tip having an elongated outer end 12 which is preferably split and forms a grip for holding the lead as the lead is fed therethrough. The intermediate portion 13 of the tip is preferably substantially cylindrical and forms a support for the outer end 14 of a spiral tube 15 which forms a support for guiding the lead through the pencil and to the tip.

The rear end 16 of the tip is preferably cylindrical and has formed on its end raised segmental threads 17. The tip is threaded into the tip end of the barrel 10 by rotation in the direction of the arrow shown in Fig. 9, which causes the segmental threads to form spiral grooves in the inner surface of the cylindrical end portion of the barrel. After the tip has been threaded into the barrel it cannot be turned in the opposite direction and removed since the ends 18 of the segmental threads would cut into the barrel surface and prevent such reverse rotation.

The opposite end of the spiral tube 15 is secured in a disk 20 which is fixedly secured in a ferrule 21 and it should be noted that the spiral tube which forms the support and guide for the lead extends substantially throughout the length of the barrel and pencil.

The rear end of the barrel has a conical seat 23 which receives a correspondingly shaped conical portion 24 of a plug 25, shown particularly in Figs. 1 and 5. The plug has a cylindrical

opening therethrough through which extends the tube 15. The rear end 26 of the plug 25 is spaced from the disk 20 and the ferrule 21 is rotatably mounted around the portion 27 of the plug 25. The plug 25 is fixedly secured in the conical seat 23 by any suitable adhesive.

The ferrule 21 has formed on the inner end thereof a bead 30 which terminates in a flange 31. The plug 25 has formed therein intermediate the portion 27 and the conical surface 24, a notch 33. A conical split ring 34 is secured around the conical portion 35 formed by the notch. When the ferrule is to be secured in place it is moved over the portion 27 and the flange 31 contracts the split ring 34 until the edge of the flange has passed beyond the split ring, whereupon the ring expands inside the flange 31. Thus the ferrule is held in place.

The lead is fed through the spiral tube 15 by means of a lead propelling member shown in detail in Figs. 6 and 7. This member has an arcuate portion 40 and a lug 41 extending laterally from one end of the arcuate portion 40. Viewed from the rear, as shown in Fig. 7, the arcuate portion forms wings 42 and 43. The end 44 of the arcuate portion 40, as shown particularly in Figs. 1 and 2 at 45, is curved or pointed.

The barrel 10, as shown in Fig. 4, is provided with an arcuate groove 50 throughout the major portion of its length for guiding the portion 40 of the lead propelling and feeding member along the outer surface of the spiral tube 15. The lug 41 of the feeding member extends through the spiral slot formed in the tube and engages the rear end of the lead, thus feeding the lead through the tube 15, as shown in Fig. 2.

The plug 25 is provided with a pair of ledges or shelves 51 and 52 which are adapted to engage the wings 42 and 43 on the lead propelling and feeding member 40 when when this member is retracted to the extreme rear end of its path of travel, as shown in Fig. 1. As the wings 42 and 43 engage the ledges or shelves 51 and 52, the member 40 will move laterally relative to the tube 15, thus withdrawing the lug 41 from the tube, leaving the rear end of the tube open.

The rear end of the ferrule 21 is normally closed by a reversible eraser cap 55 having an eraser 56 at one end thereof and an ornamental portion 57 at the other end thereof. Intermediate the ends thereof there is formed a laterally extending collar portion 58.

When the eraser cap is removed from the ferrule it will be noted that the outer end of the tube 15 is open to receive a lead which is dropped into the opening at the outer end thereof and will drop by gravity into the tube 15 until it engages the rear end of the lead section still in the pencil. After the lead has been dropped in the cap can be replaced and the ferrule 21 is rotated, thus rotating the disk 20 and tube 15. As the tube 15 is rotated the feeding lug 41 will move inwardly into feeding position in the tube as the wings 42 and 43 ride down the inclined ledges or shelves 51 and 52. The lead will then be fed through the tip in the usual manner.

In the form of the invention illustrated in Fig. 10 the pencil can be loaded without removing any cap. In this form the cap is formed in two sections 60 and 61.

Section 60 has an internal annular notch or groove 62 which is adapted to receive a split conical locking ring 63 which surrounds a conical portion 64 of the plug 65 cemented to the barrel 10. A thrust ring 66 is mounted in sec-

tion 60 of the cap and engages the rear edge of the locking ring 63. When section 60 of the cap is placed on the plug 65 and is pushed thereon, the ring 63 contracts into the space around the conical portion 64 until it can snap into the annular recess or groove 62.

The rear end of the spiral tube 70 extends through the plug 65 and through the portion 71 of the section 60 of the cap and is swaged outwardly or flared at its end 72. The outer or end section 61 is then cemented to section 60. Section 61 has a central opening 73 aligned with the tube 70 and flared as at 74 to facilitate the insertion of the lead in the cap and tube.

Thus when the pencil requires a refill, the lead is dropped into the opening in the cap and it is not necessary to remove any cap or other parts.

From the foregoing description it will be evident that the number of operative parts of the pencil described is held to a minimum and that the lead can be easily and quickly replenished simply by retracting the lead feeding member and dropping the lead into the outer open end of the tube 15.

A slightly different form of the invention is illustrated in Figs. 11 to 16 inclusive. In these figures a barrel 80 has a reduced front end 81 on which is rotatably mounted a sleeve 82 having a tip 83 at the outer end thereof. In Fig. 11 the rear end of the sleeve 82 is shown as bent inwardly at 84 to fit a correspondingly formed portion 85 on the barrel.

The spiral tube 86 fits tightly in the front end of the tip 83 and extends rearwardly through a central opening in the barrel but terminates at its rear end to leave a space 87 between a plug 88 and the rear end of the barrel.

A clutch tube 89 is fixed in the forward end of the spiral tube 86 and extends through the tip 83, the outer end of the clutch tube, as shown at 90, being split to form resilient fingers engageable with the lead 91 as the lead is fed through the tube 89.

The lead is fed through the spiral tube by means of a feeding member 95 which is shown in detail in Figs. 15 and 16. This member has a downwardly extending lug 96 adapted to fit in the spiral slot in the sleeve 86 and has laterally extending wings or ledges 97 and 98. The rear end of the member 95 has arcuate upwardly extending lugs 99 and 100 and a lug 101 extends inwardly intermediate the portions 99 and 100 and has a beveled end 102 forming a sharp edge. The lug 101 engages the rear end of the lead and feeds the lead through the sleeve 86. The feeding member 95 moves along the spiral slot by reason of the engagement of the lug 96 in the slot. This feeding movement is accomplished by rotating the sleeve 82 on the forward end of the barrel or relative to the barrel. This causes the spiral tube 86 to rotate relative to the barrel. The feeding member 95 is held from rotation since the portions 97 and 98 of the feeding member are disposed in a longitudinal channel 105 formed in the barrel and communicating with the central opening therein.

After the lead has been fed to its forward extreme of movement, as shown in Fig. 11, in which the front end 106 of the feeding member 95 engages a stop shoulder or abutment 107 formed in the barrel, the feeding member is retracted by a reverse rotation of the spiral in the barrel.

At the rear end of the barrel is secured a plug

110 similar in construction to the plug 24 shown in Fig. 5. This plug has a bore extending therethrough and disposed in alignment with the rear open end of the spiral tube 86 and, as shown particularly in Figs. 11 and 12, a space 111 is formed at the rear end of the spiral tube. The plug 110 has ledges 112 and 113 engageable by the portions 97 and 98 of the member 95 as this member is retracted to the position shown in Fig. 12. Furthermore, it will be noted that the recess 114 is adapted to receive the upper ends of the portions 99 and 103 and to permit the lug 101 to move out of the path of the lead as the lead is fed in through the opening 115 in the plug 110. If the lead is too long and extends in back of the initial feeding position of the lug 101, the initial feeding movement of the member 95 will cause the edge 102 at the end of the lug to engage the lead and break it as shown in Fig. 12. The engagement of the lugs 100 with surface 120 and of portion 121 of the member 95 with surface 122 in the barrel force the edge 102 to break the lead.

In the embodiment of the invention shown in Figs. 11 to 16, the lead can be easily and quickly dropped into the opening 115 after the feeding member 95 has been retracted to the position shown in Fig. 12 and the feeding movement will then cause the edge 102 to break the lead to proper length and thereafter to feed the lead longitudinally through the spiral. It will be obvious that in this embodiment the movement of the operative parts of the pencil has been reduced to a minimum and that the use of the pencil has been simplified since it is not necessary to unscrew or open up the rear end of the pencil in order to replenish the leads but merely to retract the feeding member, drop in the lead, and then start the feeding member on its operative movement.

Although certain specific embodiments of the invention have been particularly shown and described, it will be understood that the invention is capable of further modification and that further changes in the construction and in the arrangement of the various cooperating parts may be made without departing from the spirit or scope of the invention, as expressed in the following claims.

What I claim is:

1. A mechanical pencil comprising a barrel, a tip at one end thereof, a lead supporting and guiding tube having a spiral slot extending substantially throughout the length of the barrel and open at its rear end to receive a lead, a lead feeding member having a lug arranged to extend into said tube and feed the lead, and means engageable with said member in its extreme retracted position for moving the lug out of operative feeding position whereby a lead refill may be dropped into the rear end of the tube.

2. A mechanical pencil comprising a barrel, a tip at one end thereof, a rotatably mounted lead supporting and guiding tube having a spiral slot extending substantially throughout the length of the barrel and open at its rear end to receive a lead, a lead feeding member having a lug arranged to extend into said tube and feed the lead, and means engageable with said member in its extreme retracted position for moving the lug out of operative feeding position whereby a lead refill may be dropped into the rear end of the tube.

3. A mechanical pencil comprising a barrel, a tip at one end thereof, a lead supporting and

guiding tube having a spiral slot extending substantially throughout the length of the barrel and open at its rear end to receive a lead, a lead feeding member having a lug arranged to extend into said tube and feed the lead, channel means in the barrel for guiding said member longitudinally in the barrel and holding the member against rotation therein, and means engageable with said member in its extreme retracted position for moving the lug out of operative feeding position whereby a lead refill may be dropped into the rear end of the tube.

4. A mechanical pencil comprising a barrel, a tip at one end thereof, a rotatably mounted lead supporting and guiding tube having a spiral slot extending substantially throughout the length of the barrel and open at its rear end to receive a lead, a lead feeding member having a lug arranged to extend into said tube and feed the lead, channel means in the barrel for guiding said member longitudinally in the barrel and holding the member against rotation therein, and means engageable with said member in its extreme retracted position for moving the lug out of operative feeding position whereby a lead refill may be dropped into the rear end of the tube.

5. In a mechanical pencil, a barrel, a lead supporting and guiding tube therein having a spiral slot, a lead feeding member having a portion adapted to extend through the slot into the tube to feed the lead, and means for withdrawing said portion from operative feeding position in the retracted position of the feeding member.

6. In a mechanical pencil, a barrel, a lead supporting and guiding tube therein open at both ends and having a spiral slot, a lead feeding member having a portion adapted to extend through the slot into the tube to feed the lead, and means for withdrawing said portion from operative feeding position in the retracted position of the feeding member.

7. In a mechanical pencil, a barrel, a lead supporting and guiding tube therein having a spiral slot, a lead feeding member having a portion adapted to extend through the slot into the tube to feed the lead, and means engageable with said feeding member for moving one end thereof laterally away from the tube and for withdrawing said portion from operative feeding position in the retracted position of the feeding member.

8. In a mechanical pencil, a barrel, a lead supporting and guiding tube therein having a spiral slot, a lead feeding member having a portion adapted to extend through the slot into the tube to feed the lead, and means inclined away from the tube engageable with said feeding member for moving one end thereof laterally away from the tube and for withdrawing said portion from operative feeding position in the retracted position of the feeding member.

9. A mechanical pencil comprising a barrel, a tip at one end thereof, a lead supporting and guiding tube having a spiral slot extending substantially throughout the length of the barrel and open at its rear end to receive a lead, a removable cap on the pencil for normally closing the rear end thereof and closing access to the rear end of the tube, a lead feeding member having a lug arranged to extend into said tube and feed the lead, and means engageable with said member in its extreme retracted position for moving the lug out of operative feeding position whereby a lead refill may be dropped into the outer end of the tube.

10. In a mechanical pencil, a barrel, a tube therein having a spiral slot, means adapted to coat with the tube to feed lead therethrough, and means at the rear end of the tube for moving said feeding means out of operative position when said feeding means is moved to its retracted position.

11. In a mechanical pencil, a barrel, a tube therein having a spiral slot, open at its outer end to receive the lead, means adapted to coat with the tube to feed lead therethrough, and means at the rear end of the tube for moving said feeding means out of operative position when said feeding means is moved to its retracted position, whereby lead can be inserted in the rear end of the tube.

12. In a mechanical pencil, a barrel, a pencil supporting and guiding tube having a spiral slot, open at both ends, a ferrule at the rear end of the barrel, a cap in the ferrule for closing the rear end of the ferrule and of the tube, and means coacting with the spiral tube for feeding lead therethrough.

13. In a mechanical pencil, a barrel, a pencil supporting and guiding tube having a spiral slot, open at both ends, a ferrule at the rear end of the barrel, a cap in the ferrule for closing the rear end of the ferrule and of the tube, means coacting with the spiral tube for feeding lead therethrough, and means for moving said feeding means out of operative position in its retracted position.

14. In a mechanical pencil, a barrel, a pencil supporting and guiding tube therein, open at both ends, a cap at the rear end of the barrel, said cap having an opening aligned with the rear end of the tube, means coacting with the tube for feeding the lead therethrough and means in the cap engageable by said feeding means in its retracted position for moving said means out of feeding position.

15. In a mechanical pencil, a barrel, a pencil supporting and guiding tube therein, open at both ends, a cap at the rear end of the barrel, said cap having an opening aligned with the rear end of the tube, means coacting with the tube for feeding the lead therethrough, and means operable when said feeding means reaches its retracted position for moving said feeding means out of operative position.

16. In a mechanical pencil, a barrel having a longitudinal internal channel or groove, arcuate in cross section, a tube in said barrel having a spiral slot, and a lead feeding member for feeding the lead through said tube, said lead feeding member having an arcuate cross section dimensioned to fit in said groove in the barrel and having a lug movable in the tube to feed the lead.

17. In a mechanical pencil, a barrel, a plug secured at the rear end thereof and having a central bore therethrough, a tip at the front end of the barrel, a spiral lead supporting and feeding tube extending from the tip through said plug, a disk secured to the rear end of the tube, a ferrule secured over the plug and rotatable thereon, said disk being fixed in the ferrule, and means mounted in the barrel and movable longitudinally therein to feed the lead through the tube.

18. In a mechanical pencil, a barrel, a tube therein having a spiral slot, means adapted to coat with the tube to feed lead therethrough, means at the rear end of the tube for moving said feeding means out of operative position when

5 said feeding means is moved to its retracted position whereby a new lead can be inserted in the tube, and means on said feeding means engageable with excess lead extending rearwardly beyond said feeding means for severing the excess lead as the feeding means is moved into operative feeding position.

19. In a mechanical pencil, a barrel, open at both ends, a lead supporting and guiding tube mounted in the barrel and open at both ends, means coacting with the barrel and tube for feeding lead through the tube, and means for moving said feeding means out of the tube when said means reaches its retracted position, whereby a lead refill can be dropped into the open rear end thereof and into the tube.

20. In a mechanical pencil, a barrel, a tube therein having a spiral slot, means adapted to coat with the tube to feed lead therethrough, means at the rear end of the tube for moving said feeding means out of operative position when said feeding means is moved to its retracted position whereby a new lead can be inserted in the tube, means on said feeding means engageable with excess lead extending rearwardly beyond said feeding means for severing the excess lead as the feeding means is moved into operative feeding position, and means in the barrel engageable with said feeding means for forcing said severing means inwardly to sever the excess lead.

21. In a mechanical pencil, a barrel having a channel, a sleeve rotatable on the barrel and having a tip at the front end thereof, a tube having a spiral slot fixed to the tip and extending rearwardly throughout the length of the barrel and open at both ends, and lead feeding means mounted on the tube and coacting with the channel to feed the lead through the tube on rotation of the sleeve relative to the barrel.

22. In a mechanical pencil, a barrel having a channel, a sleeve rotatable on the barrel and having a tip at the front end thereof, a tube having a spiral slot fixed to the tip and extending rearwardly throughout the length of the barrel and open at both ends, and lead feeding means mounted on the tube and coacting with the channel to feed the lead through the tube on rotation of the sleeve relative to the barrel, said lead feeding means having a portion movable into the tube to engage and feed the lead.

23. In a mechanical pencil, a barrel having a channel, a sleeve rotatable on the barrel and having a tip at the front end thereof, a tube having a spiral slot fixed to the tip and extending rearwardly throughout the length of the barrel and open at both ends, lead feeding means mounted on the tube and coacting with the channel to feed the lead through the tube on rotation of the sleeve relative to the barrel, and means at the rear end of the barrel to withdraw said portion from the path of the lead when the feeding means is retracted at the rear end of the barrel.

24. In a mechanical pencil, a barrel open at both ends and having a channel, a sleeve rotatable on the barrel and having a tip at the front end thereof, a tube having a spiral slot fixed to the tip and extending rearwardly throughout the length of the barrel and open at both ends, lead feeding means mounted on the tube and coacting with the channel to feed the lead through the tube on rotation of the sleeve relative to the barrel, and means at the rear end of the barrel to withdraw said portion from the path of the lead.

lead when the feeding means is retracted at the rear end of the barrel.

25. In a mechanical pencil, a barrel, a pencil supporting and guiding tube therein, open at both ends and having a spiral slot, a cap at the rear end of the barrel, said cap having an opening alined with the rear end of the tube, and means coacting with and having a portion extending through the slot in the tube for feeding the lead therethrough.

26. In a mechanical pencil, a barrel, a pencil supporting and guiding tube therein, means for feeding lead through said tube, and a cap at the outer end of the barrel having means therein engageable by the feeding means in its retracted position for moving said feeding means out of feeding position.

27. In a mechanical pencil, a barrel, a pencil supporting and guiding tube therein, open at both ends, a cap at the outer end of the barrel having means for supporting the outer end of the tube, means for feeding lead through the tube, and means in the cap and engageable by the feeding means in its retracted position for moving said feeding means out of feeding position.

28. In a mechanical pencil, a barrel, a pencil

supporting and guiding tube therein, open at both ends, a cap at the other end of the barrel having an opening therethrough alined with the rear end of the tube and having means for supporting the outer end of the tube, means for feeding lead through the tube, and means in the cap and engageable by the feeding means in its retracted position for moving said feeding means out of feeding position.
